UNITED STATES PATENT OFFICE

158,653

SHOE OR SIMILAR ARTICLE

Donna L. Fenlason, Scarsdale, N. Y.

Application January 27, 1950, Serial No. 7,530

Term of patent 3½ years

(Cl. D7—7)

To all whom it may concern:

Be it known that I, Donna L. Fenlason, a citizen of the United States of America, residing at Scarsdale, in the State of New York, have invented a new, original, and ornamental Design for Shoes or Similar Articles, of which the following is a specification, reference being had to the accompanying drawing, forming a part hereof.

Fig. 1 is a perspective view of a shoe, showing my new design as it appears when ready to be worn; and

Fig. 2 is a top plan view of the shoe blank in a spread out condition.

My design for a shoe of the sandal type is characterized by the specific shape of the flaps on the sides and the ends thereof, in combination with the manner in which the shoe is laced, as shown in Fig. 1, all as illustrated on the drawing.

I claim:

The ornamental design for a shoe or similar article, substantially as shown and described.

DONNA L. FENLASON.
